UNITED STATES PATENT OFFICE

CAROLUS L. EKSERGIAN AND TALMON A. DAVENPORT, OF DETROIT, MICHIGAN

DESIGN FOR A DISK WHEEL

Application filed December 7, 1932. Serial No. 46,320. Term of patent 3½ years.

To all whom it may concern:

Be it known that we, CAROLUS L. EKSERGIAN and TALMON A. DAVENPORT, citizens of the United States, residing at Detroit, county of Wayne, State of Michigan, have invented a new, original, and ornamental Design for a Disk Wheel, of which the following is a specification, reference being had to the accompanying drawing, which forms a part hereof.

Figure 1 is a perspective view of a wheel embodying our new design.

Figure 2 is a side elevation of the same.

We claim:

The ornamental design for a disk wheel substantially as shown.

Signed at Detroit, county of Wayne, State of Michigan, this 30th day of November, 1932.

CAROLUS L. EKSERGIAN.
TALMON A. DAVENPORT.
